UNITED STATES PATENT OFFICE.

THEODOR M. MUELLER, OF DALTON, MASSACHUSETTS, ASSIGNOR TO PITTSFIELD SPARK COIL COMPANY, OF DALTON, MASSACHUSETTS, A CORPORATION.

IGNITION SYSTEM.

988,892.

Specification of Letters Patent. Patented Apr. 4, 1911.

Application filed November 13, 1908. Serial No. 462,397.

To all whom it may concern:

Be it known that I, THEODOR M. MUELLER, a subject of the Emperor of Germany, residing at Dalton, in the county of Berkshire 5 and State of Massachusetts, have invented new and useful Improvements in Ignition Systems, of which the following is a specification.

My invention relates to improvements in 10 ignition systems for internal combustion engines, the object of the invention being to combine with a magneto electric machine of the high potential type a stationary induction coil the primary winding of the coil 15 being included in circuit with a make and break device of any suitable construction; the secondary winding of the coil furnishing the spark current as usual.

The generator shown in outline herein is 20 claimed in Letters Patent of the United States issued to me on December 21, 1909 numbered 943,697, on an application filed February 25, 1907 for "Magneto electric machines" and is merely illustrative of the 25 form of generator employed by me.

The magnetic circuit of the coil is furnished by the magneto.

A further object of the invention consists in connecting, in parallel arrangement with 30 the coil of the primary winding, a battery, and a second make and break device being included in the connections of the primary winding of the coil whereby when the magneto is not being operated from the motor 35 the vaporous charge in the engine cylinders may be ignited from the second make and break or push button device, and the engine started. The usual condenser is arranged across the terminals of the make and break 40 devices.

Referring to the drawings forming part of this application,—the figure in this case clearly illustrates my invention.

In the drawings, the magneto, as a whole, 45 is designated by the letter *a* and is provided with the usual compound field magnets *b*, the driving end of the armature shaft being designated at *c*.

d designates extension members or por-

tions of the pole pieces that are connected 50 at their outer ends by a core member *e* which serves as a core for the induction coil *e*¹, the primary windings of which are designated at *f* and the secondary windings at *g*.

h designates a wire leading from one terminal of the secondary windings to a spark-plug shown at *i* for carrying the spark current, the other terminal of the secondary being connected by means of a wire *j* to the ground, indicated at *k*, which, in practice, 60 would be the framework of the machine. The primary wire has one terminal connected at *m* to the wire *j* (which is the ground connection) and the other terminal (by means of the wire *n*,) leads to the point *o* 65 of the make and break device *p* of any approved pattern.

The movable part of the make and break device is designated by *q* and is connected to the primary windings by means of the 70 wire *r*.

A condenser *s* is connected by means of the wire *t* to the wire *n* at the point *u* which is one side of the make and break device *p*, and the other terminal of the condenser is 75 connected by means of a wire *v*, to the elastic strip 10. The condenser *s* is employed as usual to absorb the spark at the terminals *o* and *q* and also to increase the inductive effect in the secondary winding *g* of the induction 80 coil *e*¹.

It should be understood that during the operation of the magneto the core of the induction coil *e*¹ is energized by means of the extension members of the pole-pieces, thus 85 generating an electromotive force in the primary winding and, at break of the circuit, by means of the make and break device *p*, a current is produced in the secondary winding *g* which appears at the plug *i* in the 90 form of a spark.

Referring now to the manner of producing a spark at the plug *i* when the magneto is not running: I employ a switch mechanism 7 that is pivoted at the point 8. A wire 95 9 extends from the point 8 to the wire *w*.

10 designates a thin flexible tongue having an opening 11 in its free or outer end,

the free end being located between the contacts 4 and 5. In the position of the parts shown, the tongue 10 is supposed to rest in contact with the switch 7 at 7¹. Extending 5 from the fixed contact member 5 is a wire 12 which is connected to the wire *n* at the point 13.

5¹ is a fixed contact point for the switch member 7 to engage when it is desired to 10 cut out the magneto *a*.

The operation of the construction is as follows: When the magneto is furnishing the spark current, as shown in the figure, the condenser *s* (which is connected across the 15 terminals *o* and *q* of the make and break device *p*,) serves to extinguish the spark at these terminals and to quickly demagnetize the core *e* of the coil *e*¹. The wire *t* leads from one terminal of the condenser *s* and is 20 connected to the part *o*, the wire *v* from the other terminal of the condenser *s* conveying the current to the tongue member 10 which is in contact with the switch member 7 at 7¹, and from this point to the wire 9 that is 25 connected to the return wire *w* to the other side of the make and break member *q*, as clearly shown.

When it is desired to ignite the vaporous charge and start the motor, from the seat 30 of an automobile for example, by means of the movable push button or contact member 4, the operator then forces the tongue 10 away from the switch member 7 thus breaking the contact between the switch 7 and 35 tongue 10 at 7¹. The reduced portion 4¹ of the movable member 4 passes through the opening 11 in the tongue 10 and engages the fixed contact member 5, and at the same time the surface around the opening 11 40 is engaged by the shouldered portion 4² of the movable contact member 4 and moves the tongue 10 away from the switch member 7 and breaks the circuit leading to the wire *v*, as mentioned above. The current 45 then flows from the battery *y* by the wire *y*¹ to the contact 4; and from this contact to the contact 5, wire 12, wire *n*, primary winding *f*, and wire *w* back to the other pole of the battery *y*. When the contacts 4 and 5 50 are opened, a spark will appear at the plug *i* thus starting the motor and operating the make and break devices *p*. The operator then opens the contacts 4 and 5 and allows the magneto *a* to furnish the spark current 55 as before. When the starting contacts 4 and 5 are closed, the condenser *s* is then connected across, or in parallel arrangement to the contacts 4 and 5 in the following manner: The tongue 10 is engaged by the 60 contact 4 and is connected with the wire *v*, the wire *t* being connected to the other terminal of the condenser *s* by means of the wires *t*, *n*, and 12. If it is desired to cut

out the magneto *a* the switch member 7 is moved to the contact point 5¹ which would, 65 of course, short circuit the magneto.

Referring now briefly to the operation of the system: When the engine is running, the rotation of the cam 7 of the make and break device *p* will close the circuit through 70 the primary winding *f* of the coil *e* and produce the spark current in the secondary winding which will flow to the plug *i* by means of the wire *h*.

When the engine is not running, and the 75 terminals *q* and *o* are open, if the operator wishes to start the engine he simply closes the terminals 4 and 5 to permit the current to flow from the battery *y* to the primary winding by means of the wires 12, *n* and 80 *w*. When the terminals 4 and 5 are separated, the induced current in the secondary winding will cause the spark to be produced at the plug *i*, the condenser at the same time discharging, in order to increase the 85 inductive effect of the secondary winding and extinguishing the spark at the terminals 4 and 5.

It will therefore be seen that I have produced a very simple and inexpensive means 90 for igniting the vaporous charge of an internal combustion engine, and also means for starting the engine when at rest.

The above referred to patent clearly shows the manner in which the core of the 95 coil is energized by the generator which is shown in outline only in the present case. The particular construction of the generator is not an essential part of the present case as the same is fully described and 100 claimed in my above referred to patent. In general it may be stated that the generator employed is of the inductor alternator type in which the field flux is made to surge back and forth through the core of the induction 105 coil.

What I claim, is:—

1. An electrical ignition system comprising a magneto electrical machine, an induction coil included in the magnetic circuit of the field, a make and break for the primary, a condenser connected across the terminals of the make and break device, a battery, electrical connections from the battery to the primary windings, a make and break device in said last mentioned connections, and means including the connections *v*, 10, 7, 9, *w*, *q*, *o* and *t* whereby when the last mentioned make and break device is operated the condenser will be connected 115 around the terminals of said second mentioned make and break device, and whereby a current will be produced in the secondary, as described.

2. In an ignition system, a magneto electric machine, an induction coil included in 125

the magnetic circuit of the machine, a battery, make and break devices, a condenser common to said devices, electrical connections extending from the battery, make and break devices, and the condenser to the primary winding of said coil, whereby when the make and break devices are operated

independently of each other, a current will be produced in the secondary.
